UNITED STATES PATENT OFFICE.

WILLIAM H. KLAUER, OF DUBUQUE, IOWA.

CORNER-TURN FOR GUTTERS.

1,260,778.

Specification of Letters Patent. Patented Mar. 26, 1918.

Application filed October 9, 1915. Serial No. 54,968.

To all whom it may concern:

Be it known that I, WILLIAM H. KLAUER, a citizen of the United States, residing at Dubuque, in the county of Dubuque and State of Iowa, have invented certain new and useful Improvements in Corner-Turns for Gutters, of which the following is a specification.

My invention relates to gutters and has 10 special reference to a corner turn therefor.

My invention embraces an especially formed corner turn or miter for gutter and also a method, process or steps for producing the gutter turn.

15 The object of my invention is to produce a corner turn without corner seam or obstruction of any nature, and also the formation of a tubular outer edge for strengthening and stiffening purposes.

20 In the drawings—

Figure 1 is a plan or face view of a metal form of blank;

Fig. 2 is an edge view of the same;

25 Fig. 3 is a plan view indicating a modification of the form of blank shown in Fig. 1 in the first step of the stamping or machine pressing operation;

Fig. 4 is an edge view of the structure shown in Fig. 3, looking in the direction of 30 the arrow pointing to said figure;

Fig. 5 is a section on either of lines X X of Fig. 3;

Fig. 6 is a plan view of the metal blank form after undergoing the second stamping 35 operation;

Fig. 7 is an end view of Fig. 6, looking in the direction of the arrow pointing to Fig. 6.

Fig. 8 shows a detail section of the outer turn of the metal form shown in Fig. 6, looking 40 in the direction of the arrow;

Fig. 9 is a bottom edge view of the section of Fig. 6 at the outer corner thereof;

Fig. 10 is a plan view of a metal blank section following the third step in the operation, which forms the tubular outer edge;

Fig. 11 is an end view of Fig. 10, looking in the direction of the arrow;

Fig. 12 is the same as Fig. 10, but is inserted for the purposes of diagrammatic 45 illustration;

Fig. 13 is a bottom view of the corner turn section, showing its form at the conclusion of the mechanical operations;

Fig. 14 is a section on the line a—a of 50 Fig. 12;

Fig. 15 is a detail edge view of the corner turn;

Fig. 16 is a section on the line b—b of Fig. 12.

Difficulty has always attended the use of 60 miter corner sections, first on account both of the obstruction presented by the right angle turn, and further by the miter joint breaking down where the parts become separated. I have experimented for a number 65 of years to produce the corner turn or miter section for gutters disclosed in my present application. It has demonstrated its efficiency for strength and durability and also its capability of deflection to prevent back- 70 ing of either water or debris at the corner or turn.

Referring to the completed gutter turn, 2 refers generally to the unit structure. 3 and 4 are sections disposed relatively at right 75 angles, which conform in bearing and in size to line gutter sections. 5 refers to the turn portion of the complete section, the same being extended to a greater width than sections 3 and 4. 6 refers to the inner turn of 80 the gutter and practically necessarily unrolled or flanged. 7 refers to rolled or tubular outer and upper edge portion of the gutter, which as will hereinafter be explained, being formed from a flanged member 85 cut at spaced intervals downwardly from a line conforming to a horizontal plane slightly below the center of the corner turn portion 8 of said rolled or tubular member 7, said cut members being caused to overlie 90 and when properly rolled assume conical form and interlock to form a continuation of the tubular edge member 7 having the same rigidity and strength as the uncut edges of said rolled edge. The outer extremities of the rolled edge member are cut away as at 9 to facilitate entrance of line gutter members.

The article produced by the above operations has the advantage that the curvature 100 at its outer edge portion prevents the lodgment of sediment and debris, and also serves to deflect the water flowing through the gutter. A new result is obtained in the formation of gutter turns, in that by the steps employed 105 to modify the forms progressively, ample material is afforded to draw from and the strain in drawing is so distributed that the integrality of the metal is preserved so that the article as finally produced is not weak- 110

ened or broken, and surplus material resulting from the pressing action is effectually reduced to the plane of the surface of the gutter so that no obstructions whatever appear at the turn.

5 What I claim is:

1. As a new article of manufacture, a corner turn for gutters formed from a single sheet of metal having an unbroken and unobstructed interior surface, an integral outer 10 rolled or tubular edge member, the turned portion of said tubular edge member being cut to form separate units and pressed into conical overlying impinging portions of the corner turn.
- 15 2. As a new article of manufacture, a corner turn for gutters formed from a single sheet of metal having an unbroken and unobstructed interior surface, its line members 20 depressed relatively at right angles and its corner portions curved upon conformatory lines throughout the body of said corner turn, and an integral outer rolled or tubular edge member.
- 25 3. As a new article of manufacture, a corner turn for gutters formed from a single sheet of metal having an unbroken and unobstructed interior surface, its line members 30 depressed relatively at right angles and

its corner portions expanded on cross sectional lines a greater width than that of the line members and curved upon conformatory lines throughout the body of said corner turn, and an integral outer rolled or tubular edge member, the turned portion 35 thereof being cut to form separate units and pressed into conical overlying impinging portions of the corner turn.

4. As a new article of manufacture, a corner turn for gutters formed from a single sheet of metal having an unbroken and unobstructed interior surface, its line members 40 depressed relatively at right angles and its corner portions expanded on cross sectional lines a greater width than that of the line members and curved upon conformatory lines throughout the body of said corner turn, and an integral outer rolled or tubular edge member, the turned portion 45 thereof being cut from its edge to a line conformatory with a plane substantially through the horizontal center of the tubular edge member.

In testimony whereof I have affixed my signature in presence of two witnesses.

WILLIAM H. KLAUER.
